DESIGN FOR A PARKING METER CASING

S. Lee Miller, Maywood, Ill.

Application February 5, 1938, Serial No. 74,907

Term of patent 14 years

To all whom it may concern:

Be it known that I, S. Lee Miller, a citizen of the United States, residing at Maywood, in the county of Cook and State of Illinois, have invented a new, original, and ornamental Design for a Parking Meter Casing, of which the following is a specification, reference being had to the accompanying drawing, forming a part thereof, wherein,—

Figure 1 is a front elevation of the parking meter casing showing my new design;

Fig. 2 is a top plan view thereof;

Fig. 3 is a rear elevation; and

Fig. 4 is a side elevation of the same.

I claim:

The ornamental design for a parking meter casing, as shown.

S. LEE MILLER.
